METHOD AND APPARATUS FOR FORMING
SLEEPERS IN BUILDING CONSTRUCTION

Clarence Le Roy Olson, San Francisco, Calif.

Application January 10, 1950, Serial No. 137,713

3 Claims. (Cl. 25—118)

1

This invention relates to a method and apparatus for forming sleepers in building construction, and more particularly to such method and apparatus for forming sleepers of moldable cementitious materials upon which wooden flooring may be supported in building construction.

In order to nail flooring to sleepers it is apparent that such sleepers must be readily penetrable by nails and adapted to hold the nails tenaciously, yet resistant to fracture. In comparison with wooden sleepers, the poured cementitious sleepers are relatively imperishable. The composition material of which the sleepers are formed is a pourable semi-liquid or fluent aggregate as a mass and is capable of molding in forms and setting in situ in the same manner as Portland cement aggregate. Such material is a well known commercial product consisting generally of suitable nail penetrable aggregate bonded by magnesium chloride.

In standardized construction such sleepers are laid or formed on 16 inch centers and usually the upper floor-supporting face thereof is provided with a width of 2½ inches, whereas it is desirable that the base shall be between 3 and 4 inches wide. The height of the sleepers is usually a minimum of 2 inches. Such dimensions, however, are not intended as a limitation of the invention and are specified as illustrative of standard and usual practice.

Briefly the invention includes apparatus for forming the sleepers comprising an assembly of a frame having a molding form portion, a leveling member for a series of the frames, and means to raise the frame from a supporting slab to the leveling member, and in placement of a plurality or series of such frames in proper spaced sequence on a supporting slab and raising the molding form portions of the frame to a uniform plane or level against the leveling member and pouring and properly troweling the cementitious matter in the space or forms provided between adjacent frames.

Frequently, and almost universally, the underlying or supporting cement slabs upon which the sleepers are based is not precisely smooth and level or in a uniform plane, and in building the usual wooden forms for pouring such sleepers all irregularities of plane of the supporting slab must be individually considered and compensated in the wooden frames.

Among the objects of the invention are to eliminate wooden sleepers and to provide a method for eliminating the labor and expense of con-

2

structing wooden forms for pouring cementitious sleepers.

Another object is to provide means and methods for forming cementitious sleepers of uniform level or plane at the upper or nailing face thereof.

A further object is to provide means and method for forming cementitious sleepers in which irregularities in a supporting slab or base may be readily compensated to provide uniformity of plane of the upper or nailing face of the sleepers.

A still further object is to provide a means and method of forming flooring sleepers whereby a predetermined width of nailing surface of the sleepers may be readily altered, if desired.

One form in which the invention may be exemplified is described in the specification herein, supplemented and illustrated in the accompanying drawing, the method being described in connection with the illustrated apparatus.

In the drawing—

Fig. 1 is a perspective view of the apparatus of the invention.

Fig. 2 is a fragmentary transverse enlarged section on line 2—2 of Fig. 1.

Fig. 3 is a fragmentary perspective of finished sleepers, showing flooring thereon.

Fig. 4 is a perspective of a frame member in open position.

Fig. 5 is a perspective of the frame member of Fig. 4 in collapsed position.

Fig. 6 is an end view of an initial operation of one manner of positioning the molding frames with leveling bar thereon, based on a concrete slab, the latter being broken and in sections.

Fig. 7 is an end view of an intermediate step in raising and supporting a leveling bar over molding frames.

Fig. 8 is an end view of a final step in supporting a leveling bar over molding frames and bringing intermediate molding frames into contact with the overlying leveling bar to provide uniform height to the upper edge of a plurality of side by side molding frames.

Referring to the drawing in which like reference characters indicate corresponding parts in the several views, 10 is a suitable concrete supporting slab of a building structure. Upon this slab are placed a plurality of elongated molding frames in suitable spaced parallel side-by-side relation. The molding frames 11 each comprises a pair of elongated angle irons of any desired length convenient for operating in filling and troweling of the sleepers formed therebetween, six to eight feet being suggested as the convenient

length. The angle irons preferably have two flanges only, disposed at 90 degrees relatively, one flange 12 being vertically disposed, and the other 13 being horizontally disposed, the horizontal flanges of the pair of angle irons being confrontingly opposed so that they are flanged inwardly relative to the completed frame and provide flat horizontal and substantially parallel strip members at the base of the frame, the vertical flanges extending perpendicular thereto at the outer edge and providing outer vertical side walls for the frame. The horizontal flanges are connected adjacent opposite ends by cross straps 14 of substantially equal length, the connection of the straps to the angle iron flanges being by pivotal connection, such as headed rivets 15 whereby the frame thus formed may be collapsed for removal from the cementitious sleeper after it is set, and also for storage or transportation purposes, by bringing the angle irons towards each other trapzoidally. In placing the frames upon a supporting slab the horizontal flanges are substantially parallel with the slab. In order to furnish a wide area for connection of the straps 14 to the horizontal flanges, it is preferred that the horizontal flanges 13 shall be substantially wider than the height of the vertical flanges 12; for example, if the vertical flanges are two inches high, the width of the horizontal flanges may suitably be between 3 and 4 inches wide. By providing the wider horizontal flanges, the cementitious mix may be spread laterally beneath the horizontal flanges when the forms are raised to contact a uniform leveling bar and the fluent mix is poured into the space between adjacent forms to form the molded sleepers A, as will be more particularly further described.

Elongated uniform leveling bars 16 are provided to transversely overlie the upper edge of the vertical flanges 12 of a series of the moulding frames, one leveling bar being disposed adjacent each of the opposite ends of an aligned series of frames. These leveling bars are rigid and preferably consist of lengths of angle irons having relatively perpendicular vertical flange 16a and horizontal flange 16b.

It is to be noted that the molding frames are raised from the supporting slab by means of elongated triangular wedges 17 which are slid under the central portion of the cross straps 14 until the upper edge of the vertical flanges of the angle irons of each frame contacts the lower face of the leveling bar. By employment of the leveling bars, it becomes unnecessary to separately compute and adjust the predetermined height of the vertical flanges of each separate molding frame. It is only necessary to first properly adjust the leveling bars to a predetermined height from the supporting slab 10, and the bottom horizontal face of flange 16b is thereby spaced from the face of the supporting slab a distance which is the predetermined finished height of the sleepers. This positioning of the leveling bar may be accomplished by any suitable supporting blocks thereunder, but since the molding frames 11 may be elevated and lowered by the wedge blocks 17 into contact with the bottom face of the leveling bars, it is preferred, in operation, that any two relatively spaced molding frame assemblies, and the wedges thereunder, may serve the purpose of elevating the leveling bars to the predetermined extent by inserting the wedges under the straps 14 until the predetermined elevation of the leveling bars has been accomplished. The leveling bars may be trued

to a true horizontal, or to an incline, by use of a spirit level.

Once having properly positioned the leveling bars by a pair of molding frames, all other molding frames beneath the leveling bars may be elevated by their respective wedges to contact the under face of the leveling bars, thus eliminating necessity of making measured adjustment of the height of any of the molding frames underlying the leveling bar, except the two which are initially employed to establish the predetermined height of the leveling bars. If independent blocks are employed to initially position the leveling bars at a predetermined height from the slab, then obviously all of the frames would similarly be raised by the wedges to contact the leveling bar.

Thus all of the frames in the series are provided with co-planar upper edges of their vertical flanges, regardless of the irregularity or unevenness of the surface of the supporting slab 10. The placing of wedges 17 under the center of the cross straps 14 has an additional advantage, in that frequently the cross straps become somewhat bent in the rough usage encountered in this type of construction, such as being stepped upon, by workmen, but by this employment of elongated triangular wedges, each frame may be raised varying amounts until the leveling bar is contacted; and when one side angle iron of the frame contacts the leveling bar, the wedge serves as a fulcrum to lift the opposite angle iron of that frame into contact with the lower face of the leveling bar, even though the cross straps 14 may be irregular or bent.

To more fully describe, by reference to figures of the drawings, the manner of raising and supporting the leveling bars 16 so that the molding frames may be raised thereagainst, it will be noted that in Fig. 1 independent wedge shaped supporting blocks 16c have been shown in the drawing as the means for raising and supporting the leveling bars 16 in predetermined spaced relation to concrete slabs, since such independent supporting blocks have the advantage of raising and supporting the leveling bars and permitting the removal of the leveling bars as soon as the fluid cement sleepers have been poured between opposed faces of the angle irons of next adjacent molding bars, so that the leveling bars and the independent supporting blocks 16c may be moved to operate with a second series of side by side molding frames while the cement between a first series of molding frames is being troweled and set. Obviously the wedge shaped blocks 16c as shown in Fig. 1 would be of greater height than the wedged blocks 17, substantially to the extent of the height of vertical walls 12 of the molding frame.

In Figs. 6, 7 and 8 the leveling bars 16 are raised to a predetermined height by first positioning a plurality of molding frames in side by side alignment on the cement slab and placing the leveling bar thereover as in Fig. 6, then raising the opposite end molding frames by means of wedges 17 under the crossed straps 14 which raises the leveling bars to a predetermined height from the slab as in Fig. 7, whereupon the intermediate or intervening moulding frames may be raised by wedges 17 to contact the bottom face of the leveling bar, as shown in Fig. 8.

The mode of operation in forming the sleepers is as follows: Assuming the laying and existence of a suitable supporting slab 10, a series of moulding frames 11 are disposed in parallel alignment,

preferably commencing at the portion of an area farthest removed from the entrance for supplies, so that the sleepers may be formed and completed progressively towards such entrance. As previously stated, it is usually desired that the sleepers shall be $2\frac{1}{2}$ inches wide and on 16 inch centers. The frames 11 are, therefore, formed so that the vertical flanges 12 of each frame are relatively spaced $13\frac{1}{2}$ inches transversely of the frame. Thus, to provide 16 inch centers for the completed sleepers of $2\frac{1}{2}$ inch width of face, the frames are placed in series so that adjacent vertical flanges of next adjacent frames are spaced apart $2\frac{1}{2}$ inches, though they may be spaced any other distance if finished sleepers of a different width are desired.

Having suitably placed the frames in series on the supporting slab 10, the leveling bars are placed thereover transversely perpendicular thereto, one leveling bar being positioned adjacent each end of the aligned series of molding frames. The leveling bars are suitably level in any well known manner, or in the preferred manner hereinabove set forth and may be trueed by spirit level or otherwise, with the bottom face thereof spaced from the supporting slab at a height which is the predetermined desired height of the finished sleepers. The molding frames 11 which have not been previously raised to support the leveling bars, are then raised from the supporting slab by means of wedges 17 until the upper edges of both of the vertical flanges 12 of each frame firmly contacts the lower flange face of the leveling bar, the elongated triangular form of the wedge serving to prevent slipping thereof when it has been inserted under the cross straps 14. The frames having been so spaced in series, and levelled, the cementitious material may be poured by any suitable means into the empty spaces between opposed vertical flanges of adjacent frames, which is the predetermined width of the sleepers, and normally is a space $2\frac{1}{2}$ inches wide. The raising of the frames from the supporting slab by means of the wedges obviously correspondingly raises the horizontal flanges 13 of the frame away from the supporting slab, and, therefore, when the fluent cementitious material is poured, portions thereof spread out beneath the horizontal flanges to provide a relatively wide base supporting the upper portion of the sleepers. After the poured material has sufficiently hardened or set, the upper surface is trowelled in the usual manner to remove surplus materials and to provide a smooth floor receiving surface, for which purpose the upper edges of the vertical flanges of adjacent frames serve as a leveling guide or form, whereby all the smooth upper faces of the sleepers are of similar elevation because such similar level has been previously established by the predetermined leveling of the leveling bars 16. After the sleepers have been uniformly levelled and smoothed, they are permitted to further set and harden in the usual manner, and then the leveling member and frames are removed for repeat of the operation, the trapezoidal collapsing of the frames assisting in such removal and moving of the frame from one operative location to another.

If desired to prevent static or dead air space between the sleepers after a floor is laid thereover, hollow ventilating tubes 18 may be imbedded in the sleepers extending through the body of the sleeper and communicating between the spaces on opposite sides thereof. It is preferred that each ventilator be placed under the horizon-

tal flanges of the frames 11 after the frames are raised by the wedges, since at that time the frames have been securely positioned by engaging the leveling bar and are not liable to be inadvertently moved from such predetermined position.

Since the purpose of the sleepers is to provide a nailed penetrable support for flooring it is to be observed that suitable flooring may be positioned thereover and nailed in the usual manner, using subflooring 19 and finished flooring 20. In some floor construction, such as in gymnasiums, it is desirable to provide some degree of resilience or springiness to the flooring, and this may be accomplished by placing a floor supporting frame work upon the sleepers prior to installation of the flooring boards.

However, the flooring, whatever its nature, is not a part of the invention, since it is only a form of use of the sleepers, and the method of forming the sleepers and the apparatus employed is the same regardless of the type of overlying flooring employed.

Having described the invention, what is claimed as patentable is:

1. A method of forming sleepers in building construction comprising the steps of arranging on a supporting slab base a plurality of elongated molding frame members in parallel side-by-side alignment and relatively spaced relation, placing a leveling bar member transversely over each of the opposite end portions of the plurality of spaced frames, positioning the bottom face of the leveling bar in predetermined spaced relation above the slab base and in overlying spaced relation to at least some of said molding frames, raising said last mentioned frames from the slab and into contact with the bottom face of the leveling member, providing a free space between the supporting slab and the bottom of the molding frames, filling the space between opposed faces of adjacent molding frames with cementitious sleeper-forming material and flowing a portion of the cementitious material into said free space to make the base of the sleeper wider than the sleeper portion between the molding frames, and removing the frames after the cementitious material has formed a set.

2. A method of forming sleepers in building construction comprising the steps of arranging on a supporting slab base a plurality of elongated transversely collapsible folding frame members relatively spaced in parallel side-by-side alignment, placing a leveling bar member transversely over each of the opposite end portions of the plurality of spaced frames, raising the leveling bar to a predetermined spaced relation overlying at least some of the moulding frames, leveling said bar in said predetermined spaced relation, raising said frames from the slab by elevating pressure transversely centrally of the frame until the frames are in contact with the bottom face of the leveling member, providing a free space between the supporting slab and the bottom of the molding frames, filling the space between the opposed faces of adjacent frames with cementitious sleeper-forming material and flowing a portion of the cementitious material into said free space to make the base of the sleeper wider than the sleeper portion between the molding frames, and transversely collapsing and removing the frames after the cementitious material has formed a set.

3. In apparatus for forming moldable cementitious flooring sleepers on a supporting slab, com-

prising an elongated collapsible frame, a leveling bar of a length sufficient for transversely overlying a plurality of said frames in parallel side-by-side alignment, means to support said leveling bar in spaced relation from the supporting slab, said frame having a pair of parallelly spaced elongated angle-iron bars, each of which has a vertical flange at the outward side of the frame and a horizontal flange perpendicular thereto, the horizontal flanges being turned inwardly and being confrontingly relatively opposed, said frame including straps pivotally connected transversely of the frame between said horizontal flanges, and means for raising the frame from the supporting

slab into contact with the leveling bar comprising elongated triangular wedges adapted for entering between the supporting slab and the straps of the frame.
